UNITED STATES PATENT OFFICE.

FRED S. CARR, OF NEWTON, MASSACHUSETTS, ASSIGNEE TO CARR FASTENER COMPANY, OF CAMBRIDGE, MASSACHUSETTS, A CORPORATION OF MAINE.

SEPARABLE FASTENER.

Application filed January 9, 1926. Serial No. 80,191.

This invention aims to provide an improved separable fastener.

In the drawings, which illustrate a preferred form of my invention:

5 Fig. 1 is a front elevation of a preferred form of device;

Fig. 2 is a section on the line 2—2 of Fig. 1, being partly in elevation;

10 Fig. 3 is a section similar to Fig. 2 but showing the relation of parts during the operation of securing the socket to the stud;

Fig. 4 is a rear elevation of the socket member of the device; and

15 Fig. 5 includes a front, a side and a rear elevation of the preferred form of stud.

Referring to the drawings, I have shown a separable fastener particularly though not exclusively useful for securing vehicle curtains to the body of the vehicle.

20 The stud, as illustrated, includes a casing 1 generally circular in cross-section countersunk into the body 2 of the vehicle so that only a hexagonal flange portion 3 projects beyond the outer surface of the body. This casing is secured to the body by a screw 4 which is non-rotatably secured to the casing

substantially as shown. The contractible and expansible head and neck portion 5 of the stud is countersunk into the casing and 25 formed in substantially the same manner as described in my copending application Serial No. 719,928, filed June 14, 1924. Within the casing I have assembled a reciprocable locking element 6 normally pressed by a spring 7 into engagement with the reversely bent portions 8 of the stud to prevent contraction of the head of the stud as illustrated in Fig. 2.

30 The socket, as illustrated, is secured to a flexible curtain 9 and includes a tubular stud-engaging portion 10 having a reversely bent neck-engaging portion 11 at its free end. The socket also includes a front plate 12 and a press-button or unlocking member 13. The tubular portion 10 is located at the inner face of the curtain 9 and has a base 14 which presents a plurality of attaching prongs 16 pressed through the curtain and upset and clinched by the anvil portion 15 of the front plate, as shown in Figs. 2, 3 and 4. The press-button 13 is assembled with the socket so as to be freely reciprocable in the tubular portion 11. One end 18 of the press-button is presented at an aperture in the front plate

so as to permit manual operation from the outside of the curtain while the other end 19 which is relatively small in diameter is presented at the free end of the tubular portion 10 to engage the locking element in the stud.

Engagement of the socket with the stud may be effected by the operator placing a finger over the exposed end 18 of the press-button and pushing the socket toward the stud as shown in Fig. 3. Thus when the reversely bent portion 11 engages the head of the stud further pressure upon the end 18 of the unlocking member 13 forces the end 19 of the press-button into engagement with the locking member 6 thereby urging it out of engagement with the reversely bent portions 8 and permitting the stud to contract (Fig. 3) so that the reversely bent portion 11 may engage the neck of the stud. Upon releasing the operating finger from the press-button the spring 7 in the stud urges the locking member, together with the press-button, into the positions shown in Fig. 2 thereby positively locking the stud with the socket.

Separation of the stud and socket can only be effected by again pressing upon the end 18 of the press-button 13 to displace the locking member, at the same time pulling upon the edge of the curtain 9 to free the tubular portion 11 from the stud.

While I have shown and described a preferred embodiment of my invention it will be understood that changes involving omission, substitution, alteration and reversal of parts and even changes in the mode of operation may be made without departing from the scope of my invention which is best defined in the following claims.

I claim—

1. A separable fastener comprising, in combination, a stud member having a head and a neck portion, a cooperating socket presenting a portion for engagement with said neck to secure said stud and socket together, locking means carried by said stud for locking said stud and socket against accidental separation and lock displacing means carried by said socket for displacing said locking means to permit separation of the fastener parts, said lock-displacing means comprising a button portion at one end and a lock-engaging portion at the other

end, said lock-engaging portion being adapted to make direct contact with said locking means.

2. A separable fastener comprising, in combination, a stud member including a plurality of resilient socket engaging portions, a socket presenting a non-resilient portion for engagement with the socket engaging portions of said stud, a locking member carried by said stud for engagement with said resilient portions to lock said stud and socket together and unlocking means carried by said socket for effecting unlocking of the stud and socket, said unlocking means comprising a button portion at one end and a reduced lock-engaging portion at the other end to engage said locking means and displace it from locking position when said button portion is pressed.
3. A separable fastener comprising, in combination, a stud member including a casing, a contractible and expansible socket engaging head countersunk into said casing, a socket presenting a stud receiving portion for engagement with said head, a spring pressed locking member in said casing for engagement with said head to lock said stud and socket together and manually operable means carried by said socket for displacing said locking member to permit separation of the fastener.
4. A separable fastener comprising, in combination, a flush-type stud member including a casing countersunk into a rigid support, a socket engaging contractible and expansible head and neck portion countersunk into said casing, a cooperating socket secured to a flexible support and presenting a rigid tubular portion for entrance into said casing to engage said stud, a locking element carried by said stud for locking said stud

and socket together and an unlocking element carried by said socket for unlocking the stud and socket to permit separation thereof.

5. A separable fastener comprising, in combination, a flush-type stud member including a casing countersunk into a rigid support, a socket engaging contractible and expansible head and neck portion countersunk into said casing, a cooperating socket secured to a flexible support and presenting a rigid tubular portion for entrance into said casing to engage the neck of the stud, a spring pressed axially shiftable locking member located in the casing portion of said stud for engagement with said stud to prevent contraction of the stud and lock said socket therewith and an axially movable press-button member carried by said socket for displacing said locking member.

6. A separable fastener comprising, in combination, a flush-type stud member including a casing countersunk into a rigid support, a socket engaging contractible and expansible head and neck portion countersunk into said casing, a cooperating socket secured to a flexible support and presenting a rigid tubular portion presenting a reversely bent portion for entrance into said casing to engage the neck of the stud, a spring pressed axially shiftable locking member located in the casing portion of said stud for engagement with said stud to prevent contraction of the stud and lock said socket therewith and an axially movable press-button member carried by said socket for displacing said locking member.

In testimony whereof, I have signed my name to this specification.

FRED S. CARR.
